UNITED STATES PATENT OFFICE.

SIGMUND SCHREIBER, OF PITTSBURGH, PENNSYLVANIA.

DISPENSING APPARATUS.

Application filed July 27, 1925. Serial No. 46,433.

This invention relates to improvements in dispensing apparatus and more particularly to an apparatus for employment in hotels, cafés, restaurants, and other eating places, for dispensing sugar in regulated quantities to avoid waste and likewise avoid contamination of the bulk of the commodity.

One of the objects of the present invention is to provide an apparatus for the purpose stated which will be neat and attractive in appearance and in which the operating parts will be inconspicuous so that the apparatus will present an ornamental appearance rather than a mechanical aspect.

Another object of the invention is to so construct the dispensing apparatus that it will not be liable to become clogged but may be readily actuated to deliver the commodity therein in definite predetermined quantities. In this connection, the invention contemplates the provision of a delivery means so constructed that when, after actuation, it assumes its normal position, it will collect and retain a predetermined quantity of sugar or the like and will be adapted to be actuated to discharge this accumulated quantity of the commodity by the mere depression of a finger lever.

Another object of the invention is to so construct the apparatus that the commodity will be delivered therefrom directly into a drinking glass or cup disposed beside the base of the apparatus, accurately and without any likelihood of scattering of the commodity over the table cloth.

Another object of the invention is to so construct the dispensing means that the commodity to be dispensed will be protected from moisture and air until actual delivery from the apparatus and will, therefore, not be liable to cake.

A further object of the invention is to provide novel means whereby the commodity stored within the reservoir of the apparatus may be agitated to obviate packing or caking thereof and which means will be inconspicuous and capable of ready actuation to serve its function.

Still another object of the invention is to provide novel means for supporting and retaining napkins in neatly arranged piles upon the apparatus and in a manner to prevent their disarrangement through careless handling.

Another object of the invention is to provide an apparatus for the purpose stated

of extremely simple construction and having but few mechanical securing elements such as rivets, screws, bolts, and the like, so that the apparatus may be produced at a relatively low cost and with greater facility than would otherwise be the case.

In the accompanying drawings:

Figure 1 is a view in elevation of the dispensing apparatus embodying the invention.

Figure 2 is a vertical sectional view therethrough.

Figure 3 is a horizontal sectional view taken substantially on the line 3—3 of Figure 2, looking in the direction indicated by the arrows.

Figure 4 is a similar view taken on the line 4—4 of Figure 2, looking in the direction indicated by the arrows.

Figure 5 is a similar view taken on the line 5—5 of Figure 2, looking in the direction indicated by the arrows.

Figure 6 is a similar view on the line 6—6 of Figure 2, looking in the direction indicated by the arrows.

Figure 7 is a detail horizontal sectional view taken substantially on the line 7—7 of Figure 2, looking in the direction indicated by the arrows.

Figure 8 is a side elevation of one of the dispensing valves dismounted.

The dispensing apparatus embodying the invention includes a pedestal which is indicated in general by the numeral 1, and comprises a vertical tubular column 2 which at its lower end is provided with a supporting base indicated by the numeral 3, these parts being preferably of china or enameled or plated metal and the said base 3 having a filler plate 4 to the under side of which there is applied or secured a sheet 5 of soft rubber, the said base 3 having a depending flange 6 which extends about the margins of the filler plate 4 and sheet 5, as best shown in Figure 2 of the drawings.

The sheet 5, being of rubber, serves to prevent displacement of the dispensing apparatus when the same is disposed upon a table, through frictional contact with the surface of the table top and likewise serves to prevent scratching or marring of the polished surface of the table top. The pedestal further includes a hollow body 7 of approximately inverted conical form and rounded circumferentially at its upper portion. The hollow body 7 is united at its lower or minor end to the column 2 and is closed at its upper

end by a removable top portion which is indicated by the numeral 9, a flange 10 being provided extending circumferentially about the said top 9 to accommodate the 5 open lower end of a reservoir 11 for the commodity to be dispensed, such as sugar. The reservoir or container 11 may be of any material found suitable for the purpose but preferably of glass and is likewise preferably 10 of the bowl-like form shown in the drawings so as to present a neat and ornamental appearance, and the upper end of the reservoir is closed by a top 12 which is preferably 15 of sheet metal and is provided with a circumferential depending flange 13 which fits about the upper edge of the wall of the reservoir.

The hollow body 7 of the pedestal houses the dispensing valves of the apparatus and 20 in order that sugar may be delivered from the reservoir 11 into the measuring and dispensing valves, spouts 14 are secured at their upper ends to the top 9 of the body 7 and extend within the said body at opposite 25 sides of the axis of the column 2. Each of the conducting spouts 14 is of oblong rectangular form in cross section and comprises side walls 15 and end walls 16.

Depending bracket members 17 are secured at their upper ends to the top 9 of the body 7 of the pedestal and depend within the pedestal at opposite sides of the upper end of the column 2. The bracket members 17 occupy parallel perpendicular planes and 30 a pair of actuating finger levers are pivotally connected at their inner ends to the bracket members and are indicated in general by the numeral 18. Each of the actuating finger levers comprises a pair of parallel side members 19 which, at their inner ends, are pivotally connected as at 20 to the bracket members 17 and at their outer end portions are turned inwardly toward each other and extended in contact with 40 each other to provide a shank portion indicated by the numeral 21, this shank portion of each actuating finger lever supporting a finger button indicated by the numeral 22. The shank portions 21 of the actuating 45 finger levers extend through slots 23 which are formed in the wall of the body 8 of the pedestal and open at their upper ends through the upper edge of said wall. At this point, it will be noted that both finger 50 levers are supported by the same pivot and that each lever is movable about its pivot independently of the other lever.

The function of the finger levers 18 is to 55 actuate the measuring and delivering valves which are associated with the spouts 14 and these valves are indicated in general by the numeral 24. Each of the valves 24 is preferably formed of sheet metal and comprises side walls indicated by the numeral 25 which are of a marginal contour to conform

to the peculiar shape of the valve as a whole. The side walls 25 occupy parallel planes and extending between the side walls and united at its lateral edges thereto, is an arcuate wall which is indicated by the numeral 26, which at one end terminates in a wall portion 27 chordal to the main portion 26 and designed, when the valve is in normal position, as illustrated at the left in Figure 2, to rest against the outer side of the respective spout 14 and, when the valve is in discharging position as illustrated at the right in Figure 2, to abut at its inner end against the said outer side of the respective spout. The material constituting the wall 26, at the end of the wall opposite the portion 27, is retrorsally bent to provide one wall 28 of a delivery spout which is indicated in general by the numeral 29. The opposite wall of the spout is indicated by the numeral 30 and said spout further includes side walls indicated by the numeral 31 constituting portions of the side walls 25, the delivery end of the spout being indicated by the numeral 32. The wall 30 of the spout is continued on a curved line, as indicated by the numeral 33, and thence turned radially inwardly to provide a wall portion 34. From the portion 34, the wall is turned to provide a portion 35, and a filler of some heavy metal, such for example as lead, indicated by the numeral 36, is arranged within the space between the wall portions 34 and 35 and constitutes a counterweight to yieldably and normally hold the valve as a whole in the position illustrated at the left in Figure 2 of the drawings, movement of the valve to the position shown at the right in said figure, through depression of the respective finger lever, being against the force of gravity exerted by the filler. As a means for pivotally supporting each valve upon its respective spout 14, the side walls 16 of each spout are provided with outstanding pivot studs indicated by the numeral 37, and the side walls 25 of the respective valves are formed with recesses 25' in the inner ends of which the said studs 37 are accommodated, as clearly shown in Figures 7 and 8 of the drawings. Resilient bearing members 38 are disposed against the outer sides of the side walls 25 of the valves and each of these members is secured to the respective side wall of the valve by a screw 39 engaged through the said member near one end thereof and threaded into the said wall of the valve. The bearing member 38 is prevented from rotating by providing a stud 38' upon the side wall 25 of the valve, which stud engages in an opening formed in the member 38 between the screw 39 and the adjacent extremity of the member. At its intermediate point, the member 38 is formed with a bearing opening 40 to accommodate the respective pivot stud 37, and

shakers, mustard jars, and vinegar cruet. It will likewise be evident at this point that the recesses which receive these condiment holders are located at opposite sides of the 5 recessed portions 48 which accommodate the drinking utensils which are to receive the sugar delivered from the apparatus so that there is no interference or obstruction offered by the condiment holders supported 10 by the base.

In order that the sugar reservoir 11 may be filled with sugar and the supply replenished as occasion requires, the top 12 thereof is formed with an opening 51, as best shown 15 in Figure 3 of the drawings, and a cover or lid 52 is hinged at one side of the opening as indicated by the numeral 53 and is provided with a finger piece 54 whereby it may be swung to open and closed position.

20 In order that spoons, or, under some conditions, if desired, forks or other table utensils may be supported by the device, the body 7 of the pedestal is provided, interiorly, opposite and between the finger actuating levers 18, with compartments 55 each including an inner or rear wall 56, side walls 57, and a bottom wall 58, the compartments being open at their upper sides and having their open upper sides presented at the top 30 of the body of the said pedestal. The bottom wall 58 of each compartment is formed with one or more openings 59 so that any liquid upon the spoons or other utensils deposited within the compartments may drain 35 through these openings and thus be prevented from accumulating within the compartments. This arrangement is best illustrated in Figure 1 of the drawings.

The invention contemplates the provision 40 of means whereby the sugar or other commodity contained within the reservoir 11 may be agitated so as to loosen the same and prevent caking thereof, and with this end in view, the top 12 of the reservoir 11 is formed with an axially located opening 60 into which is secured the lower end of a tube 61 which extends vertically above the said top. A tube 62 is secured at its lower end in an opening 63 formed axially in the cover 50 9 of the pedestal body 7 and terminates at its upper end concentrically within the lower end of the tube 61. The numeral 64 indicates a hand knob which carries a pin 65 which projects into a slot 65' formed in the upper end of a tubular shaft 66 which is located concentrically within the tube 61 and rotatably fits at its lower end in the upper end of the tube 62, the hand knob 64 having a reduced shank portion 67 which 60 rotatably fits within the upper end of the said tube 61. Stirrer arms, indicated in general by the numeral 68, are fixedly supported by the tubular shaft 66 and each arm comprises a portion 69 secured at its inner 65 end to the said shaft and extending radi-

ally and downwardly therefrom, and a portion 70 which extends downwardly from the outer end of the portion 69 and is preferably somewhat curved to more or less conform to the vertical curvature of the reservoir wall 11. At this point it will be evident that by rotating the knob 64 the shaft 66 will be rotated so as to rotate the stirrer arms 68 and agitate and loosen the sugar or other commodity within the reservoir 11. 75 It will also be evident at this point that the lid or cover 12 of the reservoir may be readily removed and with it all of the parts supported thereby, inasmuch as the lower end of the shaft 66 fits rotatably and yet loosely within the upper end of the tube 62. Therefore, the parts may be disassembled to permit of cleaning and repairs if the latter should be necessary.

In order to center the shaft 66, a bushing 71 is fitted into the lower end of said shaft 66 and is secured by a pin 71 to a rod 72 which is threaded at its lower end as at 73, into a filler 74 fixed in the upper end of the column 2, the rod 72 extending vertically concentrically within the sleeve or tube 62 and in a similar position within the sleeve shaft 66. The upper end of the rod 72 is reduced and threaded as indicated by the numeral 75 and knob 76 is fitted onto the said upper end of the rod and is positioned immediately above the knob 64, it being understood that the knob 76 is fixed with relation to the base or pedestal of the device and is, therefore, stationary. This knob is preferably provided with a diametric slot indicated by the numeral 77 and this slot is designed to accommodate the lower edge portion of a menu card indicated by the numeral 78.

The invention contemplates utilizing the top 12 of the commodity reservoir 11 as a support for paper or other napkins indicated by the numeral 79, and two piles or stacks of these napkins will, in practice, be arranged at diametrically opposite sides of the tube 61, and in order to retain the napkins in place and prevent them from being either thrown away or promiscuously disarranged through handling, means is provided which will now be described. The numeral 80 indicates a pair of arms which at their inner ends are provided with yokes 81, the relatively short arms of which are provided with inwardly presented studs 82 which are pivotally engaged in openings 83 in the opposite sides of the tube 61, as best shown in Figure 3 of the drawings, the arms being in this manner supported for vertical swinging movement and being curved downwardly from their pivoted inner ends. A weight 84 is fixed to the outer end of each arm and is preferably in the nature of a spherical body of any suitable material such for example as glass, marble, or any mate-

this portion of the member is preferably somewhat widened and sprung or bent outwardly as at 40^a so that as the valve is fitted to the spout 14 and is shoved upwardly upon the lower end of the spout, the studs 37 will ride against the outturned portions 40^a, thus springing the resilient bearing members 38 outwardly until the studs engage in the openings 40, whereupon 10 the valve will be supported for rocking movement upon the spout.

In order that the members 38 may be readily sprung outwardly so as to disengage them from the studs 37 and permit of the 15 removal of the valve from the spout, the end of each member 38 opposite the end which is fixed to the side wall of the casing, is deflected outwardly as indicated by the numeral 40', thus permitting ready engagement 20 of the finger nail behind this end of each member.

The side walls 25 of each valve are provided with studs 41, and these studs engage in the members 19 of the actuating finger levers so that when either lever is depressed, the corresponding valve will be rotated from the position shown at the left in Figure 2 of the drawings to the position shown at the right in said figure. By reference to 25 Figure 2 of the drawings, it will be observed that when the valve is in the position shown at the left of said figure, sugar will flow from the reservoir or storage compartment 11 to the respective spout 14, into 30 the collecting pocket of the respective valve, which pocket is indicated by the numeral 42 and the valves are so proportioned that this pocket will be of dimensions to accumulate such quantity of sugar as would ordinarily be desired by anyone in drinking a cup of tea or coffee. This accumulation of sugar in the receiving pocket 42 of each valve is, of course, automatically effected and takes place immediately upon the valve 35 assuming the position shown at the left of said Figure 2. When it is desired to discharge the accumulated sugar from the respective valve it is only necessary to depress the respective finger button 22, thus rotating the valve to the position shown at the right in Figure 2, and discharging the sugar from the accumulating pocket through the spout 14 and through an inclined spout 43 which is fixed at its upper end to the upper 40 end of the column 2 of the pedestal of the apparatus and has its open discharge end extending through the wall of the hollow body 7 of the said pedestal.

In order to cushion the movement of each valve from one position to the other and, to a certain extent, relieve the pivots 40 of strain, a buffer 44 is mounted in the counterweight 36 and is designed to engage against one of the side walls of the respective spout 45 45 14, when the valve assumes its normal posi-

tion through the action of the said counterweight. The movement of the valve to discharging position is cushioned by a similar buffer 45 which is likewise seated in the counterweight and is designed to engage 70 the said wall of the respective spout 14, as illustrated at the right in Figure 2 of the drawings, when the finger button 22 is depressed, so that a forceful depression of the finger button will not be liable to cause injury to or disarrangement of the parts of the apparatus.

In order to prevent sugar being expelled from the spout 29 of either valve, means is provided for normally closing the discharge end of the said spout of each valve, and this means comprises a pivoted gravity closure which is indicated in general by the numeral 46 and comprises a disc-like valve body which is pivoted as at 47 between the side walls of each respective valve and, when the valve is in receiving or accumulating position as shown at the left of Figure 2 of the drawings, seats by gravity in position closing the discharge end of the spout. When the valve is actuated to deliver the sugar therefrom, as illustrated at the right in said Figure 2, the closure member 46 will swing by gravity to position uncovering the discharge end of the said spout 29, thus providing for the ready discharge of the sugar from the pocket 42 of the valve.

It will be understood at this point that immediately upon release of pressure upon the finger actuated lever of either valve and the automatic return of the valve to normal position, sugar will flow through the respective spout 14 and accumulate in the pocket 42 until the sugar reaches the level of the lower end of the said respective spout 14 so that as each valve assumes its normal position, a predetermined quantity of sugar will automatically accumulate in the accumulating or receiving pocket of the valve.

By reference to Figure 6 of the drawings it will be observed that the base 3 of the apparatus is provided, in diametrically opposite sides and below the delivery spouts 43, with concavities indicated by the numeral 48, so that a glass, cup, or mug, may be temporarily disposed within the concavities at the time the measuring and delivering valves are actuated, to properly receive the sugar delivered from the apparatus, the walls of the concavities serving to properly center the cup, mug or glass, with relation to the respective delivery spout 43. It will likewise be observed by reference to Figure 6 of the drawings, that the base is provided with broadened portions at opposite sides of its recessed portions 48 and that these broadened portions are formed in their upper sides with relatively shallow recesses 50 in which may be disposed salt and pepper

rial which will impart an attractive and ornamental appearance to the structure as a whole and, as will be observed by reference to Figures 2 and 3 of the drawings, these ball ends rest by gravity upon the upper sides of the piles or stacks of napkins and serve to hold the same in position upon the top 12 of the reservoir 11. Inasmuch as these members rest by gravity in contact 5 with the stacks of napkins, the napkins may be withdrawn one at a time without disturbing the arrangement of the stacks and, at the same time, there can be no accidental disarrangement of the stacks through the presence of breeze or through a careless handling of the napkins in withdrawing the same. Of course, in order to replenish the supply of napkins, it is only necessary to swing either arm upwardly and place a 15 new stack of napkins beneath the weighted end of the respective arm and upon the top 20 12 of the reservoir.

From the foregoing description of the invention, it will be seen that there is provided a sugar dispensing apparatus which is attractive in appearance, entirely sanitary, simple in its construction, and capable of being disassembled for the purpose of cleaning and repairing the same. It will also be evident that the reservoir may be readily replenished with sugar by merely lifting the two corners of the stacks of napkins which overlap or overlie the lid 32 and then swinging the lid upwardly to permit of the introduction of the sugar. It will likewise be evident that in the event sugar should become caked through moisture, in the accumulating valves, the valves may be bodily removed from the body 7 of the pedestal by outwardly swinging the spring members 33 and slipping the valves out of place.

It will further be understood that various modifications may be made in the construction and arrangement of the component parts of the apparatus and that the same may be suitably ornamented in various ways without departing from the spirit of the invention. Furthermore, it will be evident that the device is exceptionally substantial 45 in its construction and not liable to any disarrangement of its parts even under conditions of comparatively rough usage.

Having thus described the invention, what I claim is:

55 1. In dispensing apparatus, a reservoir, a

spout in communication with the bottom thereof, a delivery spout below the first mentioned spout, a measuring and delivering valve rotatably mounted upon the first mentioned spout and arranged to receive material therefrom in one position of adjustment and in another position of adjustment to deliver the material into the second mentioned spout, means for actuating the valve, and buffer elements carried by the valve for 60 coaction with the first mentioned spout to cushion the movement of the valve to the said positions of adjustment thereof.

2. In dispensing apparatus, a reservoir, a spout in communication with the bottom 70 thereof, a delivery spout below the first mentioned spout, a measuring and delivering valve having spaced side members straddling the first mentioned spout, the said first mentioned spout being provided at opposite 75 sides with resilient bearing studs, bearing members carried by the said sides of the said valve and engaging said studs, and means for actuating the valve.

3. In dispensing apparatus, a reservoir, a 80 spout in communication with the bottom thereof, a delivery spout located below the first mentioned spout, a valve having spaced side members pivotally supported upon the first mentioned spout whereby the valve may 85 be rotatably adjusted to assume a position to accumulate material delivered from the reservoir through the first mentioned spout and rotated to another position to discharge the accumulated material into the second 90 mentioned spout, and a lever pivotally mounted at one end and having an operating end, said lever having pivotal connection with the valve whereby actuation of the lever will effect rotative adjustment of the 95 valve.

4. In dispensing apparatus, a reservoir, a spout in communication with the bottom 100 thereof, a valve communicating with the spout and including spaced side walls and a connecting wall defining a material accumulating chamber, the opposite side walls of the spout having bearing studs thereon, the side walls of the valve being pivotally engaged with said studs, leaf springs carried by the side walls of the valve and having openings therein for receiving said studs as and for the purpose set forth.

In testimony whereof I affix my signature.

SIGMOND SCHREIBER. [L.S.]
